UNITED STATES PATENT OFFICE

GROVER A. REBENTISCH, OF PORTLAND, OREGON, ASSIGNOR TO NATIONAL BUREAU OF LOCATION AND STATISTICS, OF PORTLAND, OREGON, A CORPORATION OF OREGON

DESIGN FOR A COMBINATION MARKING PLATE AND REFLECTING LIGHT STANDARD

Application filed September 9, 1929. Serial No. 32,711. Term of patent 3½ years.

To all whom it may concern:

Be it known that I, GROVER A. REBENTISCH, a citizen of the United States, residing at Portland, in the county of Multnomah and State of Oregon, have invented a new, original, and ornamental Design for a Combination Marking Plate and Reflecting Light Standard, of which the following is a specification, reference being had to the accompanying drawings, forming a part thereof.

Fig. 1 is a front view of a combination marking plate and reflecting light standard embodying my design.

Figure 2 is a side view of the same.

What I claim is:

The ornamental design for a combination marking plate and reflecting light standard, as shown.

GROVER A. REBENTISCH.
